UNITED STATES PATENT OFFICE.

WALTER EVERETT MOLINS, OF LONDON, ENGLAND.

CIGARETTE-MAKING MACHINE.

Application filed September 15, 1925, Serial No. 56,520, and in Great Britain October 1, 1924.

This invention is for improvements in a device for severing a moving rod into lengths and more particularly to a device for severing a moving rod produced by a cigarette making machine of the moving or continuous rod type.

In a device of the above character it is essential to impart two distinct simultaneous movements to the cutting blade, one in a direction transverse to the axis of the moving rod and the other in the direction of the axis of the moving rod.

It has hitherto been proposed to effect these two distinct simultaneous movements of the cutting blade by reciprocating, in the direction of the axis of the moving rod, the element which carries the cutting blade and giving to the element at the same time a movement independent of the reciprocation which effects the transverse movement of the blade.

The above principle involves the reciprocation of heavy, unbalanced parts and it is an object of the present invention to obviate the reciprocation of such heavy, unbalanced parts and to provide a balanced system in which the element which carries the blade and effects the transverse movement of the same relative to the rod does not reciprocate. The present invention consists of a cutting device for severing a moving rod into lengths which comprises a blade or blades carried by and adapted to revolve about the axis of a shaft secured against axial displacement and means (for example a swash plate mechanism) adapted to move the blade or blades in the direction of the axis of the shaft.

Further the present invention consists of a cutting device for severing a moving rod into lengths which comprises a rotatable shaft, a blade or blades carried by the shaft so as to pivot about an axis or axes inclined to the axis of the shaft, and means adapted to move the blade or blades about the pivotal axis or axes thereof as the shaft rotates. Again the present invention consists of a cutting device for severing a moving rod into lengths which comprises a shaft secured against axial displacement, a blade or blades operatively connected to said shaft and adapted to rotate about a fixed point on said shaft in a plane or planes inclined to the direction of the axis of the moving rod and means operable to maintain each blade

normal to the direction of the axis of the moving rod throughout the entire path of the blade.

Further the present invention consists of a cutting device for severing a moving rod into lengths wherein a blade or blades operatively connected to a shaft secured against axial displacement is or are rotatable about the axis of the shaft in an elliptical path.

It will be understood that fixed knives may be used instead of the rotary discs above mentioned.

Other methods of obtaining the lateral stroke of the knives are illustrated and will be described later.

The invention as applied to a cigarette cutting machine is illustrated in the annexed drawings, in which:

Figure 1 is an elevation of a machine constructed in accordance with this invention.

Figure 2 is a plan view with links in a different position from that of Figure 1.

Figure 3 is a section on the line 3-3 of Figure 2, and

Figure 4 is a detailed view showing a method of driving a circular cutter.

Figures 5, 6, 7 and 8 show modifications.

The main shaft 1, driven from the main drive of the cigarette making machine, is carried in bearings 2 mounted in a gear box 3 secured to the bed 4 of the machine.

To the shaft 1 is secured a gear 5 which meshes with a gear wheel 6 which is mounted on a cross shaft 7 adapted to rotate in bearings 8 mounted in the gear box.

Secured to one end of the shaft 7 is a spur gear 9 which meshes with a gear 10, secured to a further shaft 11 mounted in bearings in a gear box 12, in which is a gear wheel 13, which co-operates with another gear 14 secured to a vertical shaft 15.

Mounted at the upper part of this shaft 15 is a grooved wheel or ledgerplate 16, the groove 16^a serving to receive the rod of tobacco to be cut into lengths. The ledgerplate 16 is formed with a plurality of slots 17, preferably four in number, into which the cutting knives are adapted to project when cutting is to take place.

Provision is made for the adjustment of the plate 16 by mounting it on a bush 18, which is secured to the spindle 15 by a pin, the ledgerplate being in turn secured to the bush 18 by screws 19 passing through slots 20 as shown in Figure 2.

On the inner end of the main shaft 1 is a cross spindle 21 and also fixed to the main shaft is a second cross-spindle 22 arranged parallel to the spindle 21. Pairs of links 23 and 24 are pivotally mounted on the ends of the spindles 21 and 22 respectively, the ends of these links being connected by pins 25 to cross links 26. The links 24 are connected together by distance pieces 27, 10 and the links 23 by bridge pieces 28, and through the centre of the latter are bolted pins 29, which enter the lugs of a forked member 30. This member 30 is formed with a shank 31 which rotates in bearings in a bearing block 32, adjustably secured to a bracket 33 fixed to the bed plate 4.

The links 26 have extensions 26^a to which are connected knife carriers 34 to which the cutting knives 35 are secured by means of 20 clamps 36.

When the main shaft 1 is rotated, rotary movement is imparted to the whole link construction, but the links 23, owing to the fact that they are secured to the inclined 25 fork member 30, are caused also to oscillate, and this movement being transmitted to the knives 35, the latter are given a movement of an elliptical nature. The displacement velocity of the knives, due to their universal 30 movement, corresponds approximately at the cutting point to that of the cigarette rod.

The guide along which the tobacco rod is fed is shown at 37.

The eccentricity of the knife edge relatively to the centre of rotation combined with the increase in diameter of the knife path as the links reach a position at right angles to their original position is sufficient to cause 35 a knife to sweep gradually across the path 40 of the cigarette rod and cut it. The mechanism normally required to feed the knife is eliminated.

The knives may conveniently be of segmental shape as shown in Figure 3, but may 45 if desired be circular or other suitable shape.

Either kind of knife may be rotated if desired, provision being made for timing the segmental knife when this is done.

When it is desired to rotate the knives, a 50 driving wheel 38, as shown in Figure 4, is mounted on the forked member 30, this wheel 38 being fitted with a rubber band 39 that is adapted to engage with a pulley 40 mounted on a knife spindle. As the link-work rotates, the movement is imparted to the knives through the driving wheel 38 and pulley 40.

Variation in the length of the cigarettes may be obtained by varying the speed of rotation of the knife blades in relation to that 55 of the cigarette rod.

It is also necessary to use a ledger wheel of a different size, driven at a suitable speed and to adjust the knives to co-operate with it.

60 Figure 5 shows another method of rotat-

ing the cutters on their spindles. In this case a fixed gear 41 is held in the bracket 33. Two small gears 42 are mounted on pins 43 which are carried by a plate 44 running on the shank of the sun gear 41. Connections 70 to the knife spindles 45 are made by universal shafts 46. As the framework revolves, the planet wheels 42 are caused to rotate by the sun wheel and turn the knives.

75 Figure 6 shows diagrammatically an alternative means of obtaining the lateral movement of the knives. Each knife carrier is furnished with a roller 47 which works against a fixed cam 48 secured to the machine bed. In Figure 7 a somewhat similar 80 arrangement is shown, but in this case a plain disc 49 or ring is used and it is carried by an angle bracket in the same way as the forked link previously described. In this 85 case the stroke may be altered by altering the inclination of the plate.

90 Figure 8 is a diagram of a modified form of Figure 1. The links nearest the knives are in this case pivoted at 50, at some distance from the main shaft centre. This causes the knives to swing through an arc as they receive their lateral movement during rotation. The lateral movement can, therefore, be reduced by an amount equal to the 95 arc.

I may, if desired, use one knife only, or in another case, duplicate the set of knives shown in Figure 1. When using one knife, a counterweight is fitted on the opposite side of the linkwork to balance the parts. The single knife framework requires to rotate at twice the speed of the arrangement shown in Figure 1 for any given set of conditions and the actual cutting speed is, therefore, greater. A further alternative for obtaining the lateral movement is to connect a point in the rear link with a point eccentric to the main shaft by means of a universal shaft. In this way an effect similar to that produced by the forked piece is produced.

100 The invention is also adapted for use with a common reciprocating ledger plate.

105 What I claim as my invention and desire to secure by Letters Patent is:

110 1. A cutting device for severing an axially moving rod into lengths comprising a shaft secured against axial displacement, a blade carried by and revolving about the axis of the shaft, and means, whose effective 115 operation is dependant upon the revolution of the blade about the axis of the shaft, for moving the blade in the direction of the axis of the shaft.

120 2. A cutting device for severing an axially moving rod into lengths comprising a rotatable shaft secured against axial displacement, a blade operatively connected to said shaft and revolving about the axis of said shaft, and means, whose effective operation 125 is dependant upon the revolution of the 130

blade about the axis of the shaft, for moving the blade in the direction of the axis of the shaft.

3. A cutting device for severing a moving rod into lengths, comprising a rotatable shaft secured against axial displacement, a blade carried by said shaft and pivotally mounted for pivoting about an axis inclined to the axis of the shaft, and means moving the said blade about the pivotal axis as the shaft rotates.

4. A cutting device for severing a moving rod into lengths comprising a shaft secured against axial displacement, a blade carried by and revolving about the axis of the shaft, means, whose effective operation is dependant upon the revolution of the blade about the axis of the shaft, for moving the blade in the direction of the axis of the shaft, and mechanism to vary the extent of movement of the blade in the direction of said axis.

5. A cutting device for severing a moving rod into lengths comprising a shaft secured against axial displacement, a blade carried by and revolving about the axis of the shaft, means, whose effective operation is dependant upon the revolution of the blade about the axis of the shaft, for moving the blade in the direction of the axis of the shaft, and mechanism maintaining the plane of the blade normal to the axis of the moving rod.

6. A cutting device for severing a moving rod into lengths, comprising a shaft secured against axial displacement, a blade carried by and revolving about the axis of the shaft and means for moving the blade in the direction of the axis of the shaft in such a manner that the distance of said blade from the axis of the shaft varies continuously from a maximum to a minimum twice during each revolution.

7. A cutting device for severing a moving rod into lengths, comprising a rotatable shaft secured against axial displacement, an arm pivotally mounted on said shaft, a blade carried by said arm, and means moving said arm about the pivot as the shaft rotates.

8. A cutting device for severing a moving rod into lengths comprising a rotatable shaft secured against axial displacement, an arm pivotally mounted on said shaft, a blade carried by said arm, means moving said arm about the pivot as the shaft rotates, and mechanism maintaining the plane of the blade normal to the axis of the moving rod.

9. A cutting device for severing a moving rod into lengths comprising a rotatable shaft secured against axial displacement, an arm mounted on said shaft and pivoted at right angles thereto, a second arm mounted on said shaft and pivoted at right angles thereto and parallel to said first arm, a tie rod pivotally connected to the two arms to maintain them in said parallel relation, a

blade mounted on said tie rod, and means moving said parallel arms about their pivots as the shaft revolves.

10. A cutting device for severing a moving rod into lengths comprising a shaft secured against axial displacement, a blade operatively connected to said shaft and rotating about a fixed point on said shaft in a plane inclined to the axis of the moving rod, and means maintaining the plane of said blade normal to the direction of the axis of the moving rod.

11. A cutting device for severing a moving rod into lengths, comprising a shaft secured against axial displacement, a blade, mechanism rotating said blade about said shaft in a plane inclined to the axis of said shaft, and means varying the inclination of the plane of rotation to the axis of said shaft.

12. A cutting device for severing a moving rod into lengths comprising a shaft secured against axial displacement, a parallel link device pivotally mounted on said shaft, a blade carried by said device, and means for moving the parallel link device to cause the blade to periodically intersect the path of the moving rod and to move in the direction of the axis of said rod.

13. A cutting device for severing a moving rod into lengths comprising a shaft secured against axial displacement, a parallel link device pivotally mounted on said shaft, a blade carried by said device, means for moving the parallel link device to cause the blade to periodically intersect the path of the moving rod and to travel about the axis of the shaft as center in such a manner that the distance of said blade from the axis of the shaft varies continuously from a maximum to a minimum twice during each revolution.

14. A cutting device for severing a moving rod into lengths comprising a shaft secured against axial displacement, a cutting blade, and mechanism for rotating said blade about the axis of said shaft in such a manner that the distance of the blade from the axis of the shaft varies continuously from a maximum to a minimum twice during each revolution.

15. A cutting device for severing a moving rod into lengths, comprising a rotatable shaft secured against axial displacement, a parallel link mechanism pivotally mounted on said shaft, and including a link maintained parallel to the axis of said shaft, a blade mounted on said link, and means shifting said link in the direction of axis of said shaft in such a manner that the distance of the link from the axis of the shaft varies continuously from a maximum to a minimum twice during each revolution.

16. A cutting device for severing a moving rod into lengths, comprising a rotatable

shaft secured against axial displacement, a parallel link mechanism pivotally mounted on said shaft and including a link maintained parallel to the axis of said shaft, a blade mounted on said link, means for shifting said link in the direction of the axis of said shaft in such a manner that the distance of the link from the axis of the shaft varies continuously from a maximum to a minimum twice during each revolution, and structure ¹⁰ for balancing said blade about its axis of revolution.

In witness whereof I have hereunto set my hand.

WALTER EVERETT MOLINS.
